United States Patent Office

Des. 184,860
Patented Apr. 14, 1959

184,860

SAW HANDLE

Raymond C. Dreier, Chicago, Ill., assignor to Dreier Brothers, Inc., Chicago, Ill., a corporation of Illinois

Application September 20, 1957, Serial No. 47,794

Term of patent 14 years

(Cl. D93—4)

Fig. 1 is a side elevational view showing a saw handle embodying my new design;

Fig. 2 is a top plan view of the handle;

Fig. 3 is an end view of the handle as seen from the right of Fig. 1;

Fig. 4 is a bottom view of the handle; and

Fig. 5 is a cross-section taken substantially along the line 5—5 in Fig. 1.

I claim:

The ornamental design for a saw handle, substantially as shown.
